Primary Examiner—Cathy Anne MacCormac

(57) **CLAIM**

I claim the ornamental design for a printer, as shown and described.

DESCRIPTION

FIG. 1 is a top perspective view of a printer showing my new design;

FIG. 2 is a front elevational view thereof;

FIG. 3 is a top plan view thereof;

FIG. 4 is a left-side elevational view thereof;

FIG. 5 is a right-side elevational view thereof;

FIG. 6 is a rear elevational view thereof; and,

FIG. 7 is another top perspective view of showing the control panel in an alternate position.

The broken lines in the drawings are for illustrative purposes only and form no part of the claimed design.
